[57] CLAIM

The ornamental design for a handle for kitchen tools and gadgets, as shown and described.

DESCRIPTION

FIG. 1 is a perspective view of a handle for kitchen tools and gadgets, showing our new design;

FIG. 2 is a top plan view thereof;

FIG. 3 is a side elevational view of one side thereof;

FIG. 4 is a bottom plan view thereof;

FIG. 5 is a side elevational view of the other side thereof;

FIG. 6 is a rear elevational view thereof; and,

FIG. 7 is a front elevational view thereof.

The broken line showings of a turner in FIGS. 1-7 are for illustrative purposes only and form no part of the claimed design.

The characteristics feature of the design resides in the handle being provided with a metal cover on the top and bottom portions thereof with round resilient finger grips extending through both top and bottom metal covers of the handle. The solid black shading on FIGS. 1-7 represent the color black.
